UNITED STATES PATENT OFFICE.

WILLIAM F. BOHLING, OF ARCADIA, AND JULIUS C. BOHLING, OF GLIDDEN, IOWA.

MANURE-LOADER.

981,052.

Specification of Letters Patent. Patented Jan. 10, 1911.

Application filed March 8, 1909. Serial No. 482,195.

To all whom it may concern:

Be it known that we, WILLIAM F. BOHLING and JULIUS C. BOHLING, citizens of the United States, residing, respectively, at 5 Arcadia and Glidden, in the county of Carroll and State of Iowa, have invented a new and useful Manure-Loader, of which the following is a specification.

The object of this invention is to provide 10 an improved mechanism for elevating and loading substances spread or piled on the ground, such as manure.

Our invention consists in the construction, arrangement and combination of elements 15 hereinafter set forth, pointed out in our claims and illustrated by the accompanying drawing, in which—

Figure 1 is a plan of the complete machine. Fig. 2 is a vertical section of the 20 machine on the indicated line 2—2 of Fig. 1. Fig. 3 is a side elevation of the machine. Fig. 4 is a plan of a portion of the machine taken on a line beneath the elevator thereof. Fig. 5 is a detail elevation, on an enlarged 25 scale, of one member of feeding apparatus employed in the machine. Fig. 6 is a cross-section on the indicated line 6—6 of Fig. 5. Fig. 7 is a cross-section on the indicated line 7—7 of Fig. 5. Fig. 8 is a rear end elevation of the machine, differing from other 30 views in that the location and driving means of certain conveying mechanism are shown of modified form.

In the construction of the machine as 35 shown, the numerals 10, 11 designate traction wheels which carry an axle 12. A main frame 13 is mounted horizontally with its rear end portion supported on the axle 12. The forward end portion of the main frame 40 is supported by and swiveled to a caster truck 14. A shaft 15 is mounted horizontally on and transversely of the central portion of the main frame 13. A pulley 16 is mounted loosely on the shaft 15 and oper- 45 atively connected, as by a belt 17, to an engine shaft 18 of an engine 19 carried by the rear portion of the frame 13. A clutch member 20 is feathered to the shaft 15 and is adapted to engage the pulley 16 at times. The clutch member 20 may be moved longitudinally of 50 the shaft 15 by a bell-crank lever 21 fulcrumed on the frame 13.

The engine is run in such manner as to 55 drive the upper portion of the belt 17 rearwardly as indicated by the arrow *a* in Fig. 4. A bevel gear 22 is mounted loosely on the

shaft 15 and a bevel gear 23 is mounted rigidly on a sleeve 24 on said shaft and is arranged opposite to the gear 22. A bevel gear 25 is mounted at right angles to and 60 between and meshes with the gears 22, 23. The gear 25 is journaled to the frame 13. The sleeve 24 is journaled to the frame 13 and one end of the shaft 15 journals in said sleeve. A friction clutch 26 is feathered to 65 the shaft 15 between and is adapted to connect said shaft to either of the two gears 22, 23 or to disconnect said shaft from said gears. A bar 27 loosely connects the friction clutch 26 with the frame 13 and may be 70 moved laterally by a hand lever 28 fulcrumed on said frame. The bevel gear 23 is connected, preferably by sprocket gearing 29 to the axle 12.

When it is desired to advance the machine 75 to the substance desired to be elevated and loaded into a wagon, the gear 22 is clutched to the shaft 15 and acts through the gear 25, gear 23 and sprocket gearing 29 to forward rotation of the axle 12 and traction wheels 80 10, 11. When it is desired to reverse the travel of the machine, the gear 23 is clutched to the shaft 15 and acts through the sprocket gearing 29 to reverse the rotation of the axle 12 and traction wheels 10, 11, the gears 25 85 and 22 running idly during such reverse movement.

An elevator frame 30 is provided and is supported at its rear upper end by standards 31, 32 pivoted respectively to the side 90 of the frame and to the rear ends of the sides of the main frame 13 and by standards 33, 34 similarly connecting the elevator frame and main frame at points in advance of the first standards. Stirrups 35, one of 95 which is shown in Fig. 3, formed with internal racks, are mounted on the forward end portions of the sides of the frame 13 and a shaft 36 extends through said stirrups and through the elevator frame 30 and is 100 provided with pinions adapted to engage said racks. The shaft 36 is connected, preferably by sprocket gearing 37, to a crank 38 journaled on one side of the frame 13. The crank 38 may be rotated manually and 105 rotate the shaft 36 through the sprocket gearing 37. Rotation of the shaft 36 in one direction will cause the pinions thereon to climb the rack faces of the stirrups and raise the forward lower end portion of the elevator frame 30, the standards 31, 32 and 33, 34 articulating on their pivotal connections 110

with the frame 13 to permit such movement of the elevator frame. The crank 38 may be locked against rotation by any desired means.

- 5 A drag conveyer 39 is mounted in the frame 30 and arranged for travel of its upper portion rearwardly and upwardly, as indicated by the arrow *b* in Fig. 2. The drag conveyer 39 is supported and driven 10 by a shaft 40 journaled in the upper rear end portion of the frame 30 and connected, such as by sprocket gearing 41, to one end portion of the shaft 15. The drag conveyer 39 also is supported and guided in different 15 planes by shafts 42, 43 and 44 journaled in and transversely of the frame 30. An auxiliary frame 45 is fixed to and suspended beneath the frame 30 at the upper end of the drag conveyer 39, and a delivery conveyer 20 46 is mounted for travel therein. The conveyer 46 is carried by shafts 47, 48 journaled in the frame 45. The shaft 47 is connected to the shaft 40, preferably by sprocket gearing 49, and is driven thereby. 25 As illustrated in Fig. 8, a conveyer frame 45^a may be arranged at right angles to the frame 30 and contain a delivery conveyer on shafts 47^a, 48^a, the first of said shafts being connected to the shaft 40 by bevel 30 gearing 49^a. A scraper blade 50 is mounted transversely of and projects beyond the lower forward end of the elevator frame 30. The scraper blade is inclined and has its rear upper margin overlapping the conveyer 39. Brackets 51, 52 are fixed to and project upwardly from central portions of the elevator frame 30 opposite each other and a rod 53 connects the upper ends of said brackets and extends across said frame. 35 Bearings 54, in this instance four in number, are mounted loosely on the shaft 53 and project rearwardly therefrom. Rods 55, in this instance four in number, are mounted loosely through rearwardly projecting portions of the bearings 54 and extend across the shaft 53. The upper end portions of the rods 55 are threaded to receive nuts 56 and expansive coil springs 57 are mounted on said rods between, and at their opposite ends 40 impinge said nuts and the bearings 54. Arms 58, in this instance four in number, are pivoted at their rear ends to the lower ends of the rods 55 and extend downward and forward therefrom above the conveyer 45 and scraper blade 50. The arms 58 are spaced throughout the width of the conveyer 39 and scraper blade 50. The arms 58 are fixed to and rise from the forward end portions of the sides of the elevator frame 30 and a shaft 50 55 60 65 61 is journaled to said brackets and is connected, preferably by sprocket gearing 62, to the outer end of the sleeve 24. The shaft 61 is formed with a plurality of cranks, in this instance four in number, set quartering 65 relative to each other, between its bearings,

and collar bearings 64, also four in number, are mounted loosely on said cranks. The arms 58 extend through the collar bearings 64 beneath and at right angles to the shaft 61. Extension arms 65, also four in number, are mounted at their rear ends in and pivoted to the collar bearings 64 and extend forward and parallel with and above the arms 58 to points beyond the forward ends of the latter arms. Yokes 66, also four in 70 number, extend beneath and embrace pairs of the arms 58, 65 adjacent to the forward ends of the first arms. End portions of the yoke 66 are threaded to receive nuts 67, 68. A bar washer 69 is mounted on the arms of each yoke 66 and engages the upper surface of an arm 65. Expansive coil springs 70, 71 are mounted on the arms of the yokes 66 between and impinging the bar washer 69 and the nuts 67, 68 respectively. The 75 spring-held yokes 66 provide a resilient connection between the forward ends of the arms 58, 65 and said arms 65 may oscillate and articulate in the collar bearings 64. The arms 58, 65 preferably are composed of tubing, and gathering devices such as hoes 72, 80 or rakes, are mounted with their stems in and fixed to the forward ends of said bars, the gathering devices, constructed either as hoes or rakes, or partly of one and partly 85 of the other, depending at right angles to and in front of the bars on which they are 90 mounted.

It will be observed that the crank shaft 61 is rotated opposite to the shaft 40 and it is 100 the function of said shaft 61 to oscillate the arms 58 and 65 and cause the gathering devices thereon to engage and drag substances upon and across the scraper blade 50 and upon the drag conveyer 39. The nuts 56 and 105 springs 57 provide means for adjusting the tension of the arms 58 and the nuts 67, 68 and springs 70, 71 provide means for adjusting the tension of the arms 65. Shoes 73, 74 are mounted adjustably on the forward 110 ends of the sides of the elevator frame 30 and are adapted to slide on the surface of the ground and support the elevator frame relative thereto in advance of the caster truck 14.

In practical use the machine is advanced slowly and by its own power to the substance to be removed, such as manure; the scraper blade 50 penetrates beneath the substance to be removed; the gathering devices 72, actuated by the arms on which they are mounted, engage and drag portions of the substance to be removed across the scraper blade 50 and upon the drag conveyer 39; the conveyer 39 carries the substance upwardly and 120 rearwardly and deposits it upon the conveyer 46; and the latter conveyer carries the substance to be removed and delivers the same to a wagon dragged behind or driven alongside the motor-driven machine. When 125 130

the delivery conveyer is arranged as shown in Figs. 1, 2 and 3 it is necessary to bring the wagon in close proximity to the frame 13, either by driving it laterally thereof or 5 by attaching the pole of the wagon to said frame. We believe it to be preferable to arrange the delivery conveyer as shown in Fig. 8 so that it projects laterally from the path of travel of the elevating machine and can 10 deliver its contents into a wagon conveyed by separate power alongside of said machine.

Other forms and constructions of devices may be employed, and we do not limit ourselves to the precise construction and arrangement herein described.

We claim as our invention—

1. In a loading machine, the combination of a truck frame, vertical stirrups on the forward end portion of said frame and 20 formed with racks, an elevator frame pivotally mounted on said truck frame at its rear end portion and arranged with its forward end portion in front of the truck frame, a shaft extending through said stirrups and 25 journaled in the elevator frame, pinions on said shaft meshing with the racks of the stirrups, manually operated sprocket devices acting on said shaft, a two-plane elevator on the elevator frame, an auxiliary 30 frame fixed to and suspended beneath the rear end portion of the main elevator frame, an endless conveyer in said auxiliary frame, sprocket connections between the elevator and endless conveyer, gathering devices on 35 said elevator frame, a prime mover on the truck frame, and driving connections between the prime mover and elevating and gathering devices.

2. In a loading machine, the combination 40 of a truck frame, a prime mover thereon, a pair of braces pivoted at one end each to the rear end portion of the truck frame and extending upwardly and rearwardly therefrom, another pair of braces pivoted at one 45 end each to the rear end portion of the truck frame adjacent to the pivots of the first pair of braces and extending upwardly and forwardly therefrom, a two-plane elevator frame arranged above and in front of the 50 truck frame, pivotal connections between the rear end portions of the elevator frame and the upper end of the first pair of braces, pivotal connections between said elevator frame and the upper ends of the first pair of 55 braces, adjusting mechanism connecting the forward portion of said elevator frame to said truck frame, a two-plane elevator in the elevator frame, gathering devices on said elevator frame, and independent driving connections between the prime mover and elevating and gathering devices.

3. In a loading machine, the combination 60 of a truck frame, vertical stirrups on the forward end portion of said frame and 65 formed with racks, an elevator frame pivot-

ally mounted on said truck frame at its rear end portion and arranged in an inclined plane with its forward end portion in front of the truck frame, a shaft extending through said stirrups and journaled in the 70 elevator frame, pinions on said shaft meshing with the racks of the stirrups, manually operated sprocket devices acting on said shaft, an elevator in said frame, gathering devices on said elevator, a prime mover on 75 the truck frame, and independent connections between the prime mover and elevating and gathering devices.

4. In a loading machine, the combination of a truck frame, an elevator frame having 80 its upper end arranged horizontally and its forward portion arranged in an inclined plane, opposite braces pivotally connecting the rear end portion of the truck frame and the rear end portion of the elevator frame, 85 opposite braces set obliquely to the first braces and pivotally connecting the rear end portion of the truck frame to intermediate portions of the elevator frame, vertically slotted stirrups on the forward end portion 90 of the truck frame and formed with internal racks, a shaft extending through the forward portion of the elevator frame and through the slots of said stirrups, pinions on 95 said shaft meshing with the racks of the stirrups, manually operated sprocket devices adapted to rotate said shaft, a two-plane elevator on the elevator frame, a prime mover on the truck frame, sprocket connections between the prime mover and elevator, 100 gathering devices on the elevator frame, sprocket connections between the prime mover and gathering devices, and traction mechanism on the truck frame geared to 105 the prime mover.

5. In a loading machine, the combination of a truck frame, an elevator frame having its upper portion arranged horizontally and its forward portion arranged in an inclined plane, opposite braces pivotally connecting the rear end portion of the truck frame and the rear end portion of the elevator frame, 110 opposite braces set obliquely to the first braces and pivotally connecting the rear end portion of the truck frame to intermediate portions of the elevator frame, vertically slotted stirrups on the forward end portion of the truck frame and formed with internal racks, a shaft extending through the forward portion of the elevator frame and through the slots of said stirrups, pinions on 115 said shaft meshing with the racks of the stirrups, manually operated sprocket devices adapted to rotate said shaft, a two-plane elevator on the elevator frame, a prime mover on the truck frame, sprocket connections between the prime mover and elevator, gathering devices on the elevator frame, sprocket connections between the prime mover and gathering devices, traction mechanism on 120 125 130

the truck frame geared to the prime mover, an auxiliary frame fixed to and suspended beneath the main elevator frame, an endless conveyer in said auxiliary frame, and 5 sprocket connections between the elevator and endless conveyer.

6. In a loading machine, the combination of an elevator frame, and shoes arranged on opposite sides of the forward end of said frame, said shoes being formed with slots, 10

and bolts extending through said slots and elevator frame whereby said shoes may be adjusted by movement transversely of the bolts or by movements through arcs relative to said bolts.
